C. O. WHITE

HEADLIGHT

Original Filed June 8, 1920.

Inventor
Clayton O. White

By *Richard J. Cook*
Attorney

UNITED STATES PATENT OFFICE.

CLAYTON O. WHITE, OF SEATTLE, WASHINGTON, ASSIGNOR TO WHITE-WAY CO., OF SEATTLE, WASHINGTON, A CORPORATION OF WASHINGTON.

HEADLIGHT.

Application filed June 8, 1920, Serial No. 387,359. Renewed May 17, 1922. Serial No. 561,750.

To all whom it may concern:

Be it known that I, CLAYTON O. WHITE, a citizen of the United States, and resident of the city of Seattle, county of King, and State of Washington, have invented certain new and useful Improvements in Headlights, of which the following is a specification.

This invention relates to new and useful improvements in headlights, and more particularly to headlights of that character especially useful on motor vehicles; the principal object of the invention being to provide a combination which embodies features of the usual automobile spot light and anti-glare headlight whereby a central shaft of light of effective intensity may be projected directly forward of the light, and whereby other rays may be projected in a less intensified beam that will substantially light up a roadway forward of a vehicle equipped with the light but will produce no glaring effect outside of the spot light beam, and other rays will be reflected laterally to both sides of the roadway.

In accomplishing this and other objects of the invention, I have provided the improved details of construction, the preferred forms of which are illustrated in the accompanying drawings, wherein—

Figure 1 is a central sectional view of a headlight constructed according to the present invention.

Figure 2 is a front view of the same.

Figure 3 is a transverse, sectional view on the line 3—3 of Figure 1.

Referring more in detail to the several views of the drawings, wherein like reference numerals designate like parts—the numeral 1 designates a reflector body, which may be made in any desirable or suitable size and of any desirable material suitable to its particular use, and which consists of a short cylindrical portion 2 which, at its forward edge is turned to form a peripheral flange 3 and continues at its opposite end into a truncated, conical portion 4 which terminates in a spherically curved end section 5; the center about which the spherical reflecting surface is formed being in the axial line of the conical and cylindrical reflecting surface.

Forwardly of the reflecting surface 5 is an electric lamp 6 which may be mounted and adjusted in any of the well known ways

now employed, and electrically connected with circuit wires for supplying electricity thereto.

The intermediate, or conical portion 4 of the reflector body has ribs or ridges, 7, formed therein which extend in the general axial direction of the cone at regular distances apart with the body portion concaved transversely between the ribs, as is particularly illustrated in Figure 3, forming depressions 8 intermedial the ribs which extend the length of the conical portion.

A housing 9 is formed to receive the reflector body, and this preferably is provided with an inturned flange at its open end against which the flange 3 may seat. Also a ring member 10 is applied to these parts to hold them functionally together and also secure a glass plate or lens 11 at the front of the housing as is ordinarily done.

In using a headlight of this character, the lamp 6 is located in, or adjusted to such position, that the best results will be gained from the spot light reflecting surface; that is, so that it will cast a narrow and intense shaft of light directly forward of the reflector.

It is apparent also that the shaft of light produced or thrown out by the spherical or spot light reflecting surface, will be surrounded by a much less intense light reflected from the ribbed conical reflecting surface 4, which, being so ribbed, will effectively diffuse all light rays reflected therefrom that no undesirable glaring effect is produced and a roadway forward of a vehicle, equipped with such a light will be plainly visible.

It is also noted that the cylindrical reflecting surfaces 2 will cause other rays of light to be cast laterally of the direction of light from the other surfaces and will serve to illuminate objects adjacent opposite sides of the roadway.

It is to be understood that the extent of the spherical and cylindrical reflecting surfaces and conical surface 4 are subject to modification and I do not wish to be limited to the exact form as illustrated.

Having thus described my invention, what I claim as new and desire to protect by Letters Patent, is:

In a headlight, in combination, a reflector body comprising a truncated conical reflec-

tor surface terminating at the smaller end in a spherically curved reflecting surface formed about a center which lies in the axial line of the conical portion, and at its 5 end extended into a cylindrical reflecting surface; said conical body portion having inwardly pressed ridges extending longitudinally thereof and concaved outwardly between said ridges, and a lamp located forwardly of the spherical reflecting surface and in the axial line of the cone.

Signed at Seattle, Washington, this 27th day of May, 1920.

CLAYTON O. WHITE.
